UNITED STATES PATENT OFFICE.

WALTER J. KRAUSE, OF CHICAGO, ILLINOIS.

CRANE-BRAKE.

1,261,245.

Specification of Letters Patent.

Patented Apr. 2, 1918.

Application filed March 2, 1916. Serial No. 31,622.

To all whom it may concern:

Be it known that I, WALTER J. KRAUSE, a citizen of the United States, and resident of Chicago, in the county of Cook and State 5 of Illinois, have invented certain new and useful Improvements in Crane-Brakes, of which the following is a specification.

My invention relates to cranes, and has particular reference to a novel brake adapt- 10 ed for use in connection therewith.

It is common practice to provide in connection with the hoisting mechanism of traveling cranes, means for positively controlling the lowering movement of the load, 15 such means being operative only during the lowering and not during the raising movement. Such means usually comprise a lock applied to the large gear on the shaft of the hoisting drum, the lock commonly being 20 in the form of a pinion in constant engagement with the gear, means being provided for applying braking force to the pinion.

An object in the construction of my de- 25 vice is to provide a lock applicable to the pinion, as is common, but which lock shall be in the form of a frictional engagement between two conical surfaces, there being no positive engagement as between intermeshing teeth which might become broken under 30 an excessive shock.

The invention will be more readily understood by reference to the accompanying drawings, wherein—

Figure 1 is a vertical section through a 35 crane brake constructed in accordance with my invention;

Fig. 2 is a side elevation of one side of the construction shown in Fig. 1, while

Fig. 3 is a similar view of the opposite 40 side of the construction.

In the drawings it will be seen that the shaft 10, which may be connected to the hoisting cable drum, is provided with the usual friction disks 11, 12, which are opera- 45 tively connected to the large gear 13. Inasmuch as these parts operate in a well-known manner, they will not be specifically described. A pinion 14 meshes with the gear 13 and is loosely mounted on a shaft 50 15, having a squared head 16, which is seated within a bearing member 17. This member 17, as best shown in Fig. 2, is squared and is held within a similarly shaped recess in the casing 18. The opposite end of the 55 shaft 15 is held within a similar bearing member 19, which is likewise squared and

fitted within a similar opening in the main casing 18. The pinion 14 is provided on one side with an extension or sleeve 20, having on its edge a pair of laterally extending teeth, which are formed by the shoulder 2 and the inclined plane 22. A separate sleeve 23, slidably mounted on the shaft 15, is provided on its larger end with teeth similar to but oppositely disposed with relation 65 to the teeth formed on the sleeve 20. The periphery of the sleeve 23 is in the form of a cone and is intended to fit within the conical recess 24, formed within the bearing member 17. This recess 24 may be lined with 70 a non-burning material, if desired. On the opposite side of the pinion 14 is a short extension, or sleeve, 25, which bears against a combined thrust washer and bushing 26. A clamp nut 27 is secured on the threaded 75 outer end of the shaft 15. This nut may be actuated to move the pinion 14 to the left, as viewed in Fig. 1, to compensate for any wear which may take place.

The operation is as follows: Assuming 80 the parts to be in the position of Fig. 1, which is the position they would assume while a load was being lifted, if the pinion is rotated in the direction of the arrow, it will be seen that the inclined surfaces 22, 85 on the sleeve 20 and sleeve 23 will tend to force the latter sleeve into engagement with the surfaces of the conical recess 24 and thereby to lock the sleeve and the pinion 14 against further rotation. This will tend 90 to lock the large gear 13 against rotation, and the lowering of the load will be controlled by the frictional slipping of the disks 11, 12, as required. However, as soon as the lowering action is completed and the 95 motor is reversed, the shoulders 21 on the sleeve will be brought sharply into contact and the cone 23 will be loosened from engagement with the walls of the recess and the lifting or elevating movement will be 100 free of restraint.

The parts are very simple and cannot readily become out of order. Means are provided for taking up any wear which may occur, and the parts will operate as desired 105 at all times.

I claim:

1. In a crane brake, the combination of a casing having a substantially conical seat, a brake gear mounted in said casing, a pinion in constant engagement with said gear, 111 a cone clutch member associated with said

conical seat and said pinion, and means carried by said pinion for forcing said clutch member into engagement with the seat on one direction of rotation of said pinion and 5 disengaging the same in an opposite direction of rotation, substantially as described.

2. In a crane brake, the combination of a brake gear, a pinion, a cone clutch associated with said pinion, said cone clutch including a stationary seat and a movable friction member co-operating with the seat, and wedge means associated with the movable clutch member and said pinion and adapted to force said movable clutch member into engagement with the fixed member on one direction of rotation of said pinion, substantially as described.

3. In a crane brake, the combination of a brake gear, a pinion in engagement therewith, a shaft upon which said pinion is mounted, a casing providing bearings for said shaft, one of said bearing members having a conical recess, a conical sleeve loosely mounted on said shaft and adapted to co-operate with said recess, and co-operating teeth on said conical sleeve and said pinion whereby said conical surfaces are forced into engagement on one direction of rotation of said pinion and disengaged on rotation in the opposite direction, substantially as described.

4. In a crane brake, the combination of a brake gear, a pinion meshing therewith, a shaft upon which said pinion is mounted, a casing supporting said shaft, a fixed bearing member held in said casing and providing a conical recess, a conical sleeve loosely mounted on said shaft, said sleeve and said pinion being provided with oppositely disposed shoulders and inclined surfaces leading to said shoulders, whereby on one direction of rotation of said pinion said inclined surfaces are brought into engagement and

said sleeve is forced into engagement with the walls of said conical recess and on the 45 opposite direction of rotation said shoulders are brought into engagement and said sleeve disengaged from said recess, substantially as described.

5. In a crane brake, the combination of a power shaft, a large gear frictionally engaging said shaft, a pinion in constant engagement with said gear, means for locking said pinion and said large gear, said means including fixed and movable friction cone 55 clutch members and wedge surfaces on said movable clutch member and said pinion, said surfaces being disposed in such manner as to cause the locking of said pinion when rotated in one direction and permit freedom 60 of movement when rotated in an opposite direction, substantially as described.

6. The combination of a shaft, a gear mounted on the shaft, friction members carried by the shaft and frictionally engaging 65 opposite sides of the gear, a pinion in mesh with the gear, a pinion housing, a clutch member carried by the pinion, a rotatable and endwise movable tapered friction clutch member, the two clutch members being associated for simultaneous rotation in one direction only and also provided with coöperate cam surfaces to move the movable member endwise in the other direction of movement, and said pinion housing having 70 a tapered seat for frictional engagement with the tapered clutch member when the latter is moved endwise by the other clutch member.

Signed at Chicago, Illinois, this 26th day 75 of February, 1916.

WALTER J. KRAUSE.
